BRAKE OPERATING MECHANISM

Filed July 26, 1930

UNITED STATES PATENT OFFICE

HERBERT E. BARTSCH, OF CHICAGO, ILLINOIS, ASSIGNOR TO UNIVERSAL DRAFT GEAR
ATTACHMENT CO., A CORPORATION OF ILLINOIS

BRAKE OPERATING MECHANISM

Application filed July 26, 1930. Serial No. 470,793.

This invention relates to brakes, and more particularly to brake operating mechanism for railway cars.

One of the objects of the invention is the provision of a new and improved hand brake lever device that is adapted to be attached to the end sill of a car for changing the direction of the force applied to the brake operating tension member; for quickly taking up the slack during the initial operation of the brake; and for applying increased leverage to the brake tension member beneath the car during the final operation of the mechanism in applying the brake.

Another object of the invention is the provision of a new and improved rotatable lever device for use in brake operating mechanism, whereby the mechanism is self-adjusting for compensating for variations in the lengths of cars on which the device is employed.

Another object of the invention is the provision of brake operating mechanism that is comparatively inexpensive to manufacture, simple in construction, easily installed, efficient in operation, and that is strong and durable.

Other and further objects and advantages of the invention will appear from the following description, taken in connection with the accompanying drawing, in which

Fig. 1 is a side elevation of one end of a railway car showing the invention in position thereon, with parts broken away;

Fig. 2 is an end elevation thereof, with parts broken away;

Fig. 3 is a side elevation of the sheave segment and lever, somewhat enlarged;

Fig. 4 is a section on line 4-4 of Fig. 3; and

Fig. 5 is a section on line 5-5 of Fig. 3.

Referring to the drawing, the reference character 10 designates a railway freight car on one end of which is mounted the brake operating mechanism designated generally by the character 11 and comprising a casing 12 attached to the end of the car in any suitable manner as by means of the bolts 13. Mounted within the casing 12 is a brake drum indicated at 14 by dotted lines in Fig. 2, which is adapted to be rotated by the brake wheel 15

in the usual manner. Since this mechanism is of the usual or any well known construction, it is not thought necessary to further illustrate or describe the same.

Suitable means are provided for applying the brakes to the car by operating the wheel 15, as will now be described. A combined sheave segment and lever 16 is pivotally connected to the end sill 17 in any suitable manner. As shown, the end sill is provided with a bracket 18 having downwardly extending arms 19 and 20 through which extends a pin or shaft 21 on which the sheave segment 16 is mounted.

The sheave segment 16 comprises a segment 22 having a peripheral groove 23. The segment is also provided with a downwardly and outwardly extending lever arm 24 having an opening 25 therein to which is pivotally connected the rod tension member 26.

Attached to the lower side of the sheave segment 16 is the forward end of a brake tension member 27 which, as shown, is in the form of a chain or cable. The tension member 27 may be anchored to the sheave segment in any suitable manner. As shown, the sheave segment is provided with two downwardly extending projections 28 and 29, see Fig. 4, spaced apart a sufficient distance to form a slot to receive one of the links 31 of the brake tension member 27. The projections 28 and 29 are provided above their lower ends with a groove forming a recess 32 of sufficient dimension to receive the link 33 as clearly shown in Figs. 4 and 5 of the drawing. When in operative position, the plane of the link 31 is in the plane of the sheave segment 16. The plane of the next adjacent link 33 is at right angle to the plane of the sheave segment 16 and its inner end is adapted to engage the inner end wall of the recess 32 for anchoring the tension member 27 to the segment 22.

A cotter pin or other securing member 34 is adapted to be inserted transversely through the members 28 and 29 above the recess 32 in engagement with the forward end of the link 31 for preventing the removal of said link and yet permit it to rotate about 100

the rear portion of the link 33. By inserting the pin above link, wear on the pin is reduced to a minimum. The opening for the pin is located sufficiently above the lower edge of the segment that there is little or no danger of breaking the segment at said opening.

Any suitable means may be provided for attaching the lever tension means and rod 10 26 to the drum 14. As shown, the upper end of the member 26 is attached to a clevis 40 within which a reversible lever 35 is pivoted. A cable or chain 36 has its upper end anchored to the casing 12 as at 37 and is attached at an intermediate portion to the reversible lever 35 as at 38. The lever 35 is provided with a peripheral groove 39 and the chain 36 extends in this groove about the lever 35 and has its upper end attached to 20 the drum 14, in the usual manner. The parts are so constructed that the levers 35 and 24 will be substantially in the position shown on the drawing so that upon the initial application of the brakes these two levers will 25 be operated to rapidly take up the slack, after which the lever 35 will have reversed and the lever 24 will have assumed a position more nearly at right angles to the tension member 26 whereby upon final application 30 of the brakes the maximum amount of power is applied.

The shape of the segment 16 is such that the cable or chain 27 approaches closer and closer to the pivot 21 as the segment rotates, 35 in applying the brakes, and during this time the arm 24 will become more nearly horizontal whereby it will afford its maximum leverage during the final operation in applying the brakes, and will rotate the segment 40 16 rapidly to take up the slack during the initial operation of the brake operating mechanism.

In order to compensate for variation in the lengths of cars, it is common practice to provide turnbuckles in the brake operating rods for lengthening or shortening the same. With the present invention the necessity for lengthening and shortening the brake operating tension member is taken care of by the lever 24. If the car is slightly over length the lever arm 24 will occupy a lower position when the slack is taken up than when the car is slightly under length. In other words, this variation in length is compensated for by a change in the position of the lever.

This is considered an important feature of the invention because it renders the brake 80 operating mechanism self-adjusting.

I claim as my invention:

In a railway brake, a lever comprising a segmental portion and a bearing opposite the segmental portion about which the lever 85 is adapted to turn while in use, said segmental portion being provided with a groove in its periphery and having a forwardly extending arm to which an operating member is adapted to be connected, said arm being provided with a slot, the bottom wall of which constitutes a continuation of the bottom wall of said groove and having a slot transverse to said first mentioned slot, said last named slot being closed at its rear end except for the 90 first-named slot and open at its forward end, said slots adapted to receive two adjacent links of a brake operating chain for anchoring the chain to said arm, said arm being provided with an opening adjacent to but in 100 advance of the closed end of said last named slot and above the outermost of said two adjacent links for receiving a pin for contacting the link of the brake operating chain that engages the first named slot to prevent its disengagement from said arm.
